UNITED STATES PATENT OFFICE.

NIEL DAHL, OF DENVER, COLORADO.

BICYCLE-FRAME.

SPECIFICATION forming part of Letters Patent No. 593,046, dated November 2, 1897.

Application filed October 21, 1896. Serial No. 609,524. (No model.)

To all whom it may concern:

Be it known that I, NIEL DAHL, a subject of the Emperor of Germany, residing at Denver, in the county of Arapahoe and State of Colorado, have invented a certain new and useful Improvement in Bicycle-Frames, of which the following is a specification.

My invention relates to a new and useful improvement in bicycle-frames, and has for its object to so construct such a frame as to render it more durable and more evenly equalize the strains to which it is subjected, while at the same time decreasing the vibration transmitted from the wheel to the rider, thereby rendering the riding of the machine more agreeable, while at the same time increasing the power which may be applied for the propulsion thereof.

With these ends in view this invention consists in the details of construction and combination of elements hereinafter set forth, and then specifically designated by the claims.

In order that those skilled in the art to which this invention appertains may understand how to make and use the same, the construction and operation will now be described in detail, referring to the accompanying drawings, forming a part of this specification, in which—

Figure 1 is a side elevation of a frame built in accordance with my improvement, portions thereof being broken away so as to illustrate more clearly the connection between the vital parts thereof; Fig. 2, a section at the line *x-x* of Fig. 1, and Fig. 3 a section at the line *y-y* thereof.

In carrying out my invention I construct the head *A* in many respects similar to the designs now used in bicycles, and, as is well known, this head is for the reception and guidance of the upper end of the steering-fork *B*; but as this fork forms no part of my present invention I have here shown it of the usual design.

To the head *A* is connected in any suitable manner the front brace-tube *C*, the lower end of which is connected with the crank-hanger *D* in the usual manner, and from this hanger runs upward at a suitable angle the rear brace-tube *E*. The upper section of the brace-tube *E* is connected to the head *A*, at its junction

with the front brace-tube *C*, by a curved brace-tube *F*, which corresponds in general to the top brace-tube of the ordinary bicycle; but the special feature of my design is that the tube is so curved as to sustain a greater amount of downward pressure than would otherwise be the case were it made straight, as is well known in structural ironworking. In practice I prefer to form this brace-tube of three sections—a front and rear tubular section and a central solid section *G*. These parts may be brazed or otherwise secured together, so as to become for all practical purposes a continuous brace, and the central section *G* is slotted or recessed in order that it may receive and retain the elongated lug or fin *H*, which is formed upon the under side of the spring saddle-bar *I*, and this bar is attached to the head at *J* in any suitable manner and is preferably of spring-steel of such a temper as to be suitably resilient, for the purpose hereinafter set forth.

The rear portion of the saddle-bar is slotted, as indicated at *K*, and also has a hole formed therethrough at the inner end of this slot, through which the saddle-post *L* passes and is secured in any adjustment by the tightening of the bolt *M*. A lug *N* is also formed upon the underside of the saddle-bar, through which the post passes for the purpose of giving a greater bearing to the post, as well as for the guidance of the rear end of the saddle-bar, for which purpose this lug fits within the socket *O*, which is formed upon the rear portion of the upper brace-tube *F*. The socket *O* is reduced at its lower portion and adapted for the guidance of the post *L*, while its upper end, which is of larger diameter, serves for the guidance of the lug *N*, and in practice an elastic washer or block *P* is located within the enlarged portion of the socket, and serves as a cushioning-stop for the lug *N*, so as to break the force of the impact between said lug and the bottom of the socket when the downward limit of the movement of the saddle-bar is reached.

The lug *N* is prevented from withdrawal from the socket-hole by means of a bolt *Q*, passing through the saddle-bar, as well as through the ear *R*, in which latter it is free to move up and down, so that when the sad-

idle-bar is depressed the nut S, carried by the lower end of the bolt, will move out of contact with the ear; but when the pressure which has previously depressed the bar is lessened and the bar moves upward this movement will be limited by the nut again coming in contact with the under side of the ear.

The back stays T are of usual construction and arrangement and connect the upper end 10 of the rear brace-tube to the bearings U of the machine.

In order that the saddle-bar may be relieved of sudden or undue shocks, a cushion-block V is interposed between the lug H and the 15 bottom of the groove in which said lug fits, and this block may be of rubber or other suitable material.

From this description it will be seen that a rider mounted upon the saddle supported 20 by the post L will have interposed between himself and the running-gear of the machine a resilient bar, which will act, after the manner of a long sweep carriage-spring, to absorb the vibrations of the machine occasioned by 25 its travel over the road-bed, thus permitting the up-and-down movements of the frame without affecting the general position of the rider, inasmuch as the weight of the rider will thus not have to be lifted at every little 30 elevation of the machine. The advantage of this construction becomes, therefore, obvious, in that the rider experiences greater comfort and is enabled to pass over rougher road-beds without injury to the machine or annoyance to himself, since it obviates the necessity of the rider lifting his weight from off 35 the saddle onto the pedals, the weakest point in the whole bicycle, thus relieving the rider of unnecessary efforts and the machine of 40 undue strain, as well as permitting it to pass more easily over abrupt obstructions, as is well understood in the case of spring-vehicles.

Another advantage gained by my improvement is that since the rider's position remains 45 substantially the same regardless of the vibrations of the machine he is enabled to exert a more continuous force to the pedals for the propulsion of the machine.

Another and very important advantage 50 gained by my construction is that it tends to distribute the weight of the rider more equally between the front and the rear wheel than is the case in bicycles as at present constructed.

Another general result of these improvements is that the wheel is more easily propelled, and which is especially noticeable going up an incline. Besides, experiments have also demonstrated that a bicycle thus constructed may be ridden at full speed over obstructions—such as car-tracks, holes, &c.—without the rider feeling any inconvenience or the bearings and rims suffering any hard or sharp blows from the reaction of the jolt on the frame and wheels.

I do not wish to be understood as limiting 65 myself to the exact curvature of the brace F, nor to the direction in which said brace is

curved, since it is obvious that the curvature thereof might be increased or decreased to suit the fancy of the manufacturer, or that instead of curving upward it might curve downward, in which case it would be connected to the head at or near the point J, thereby increasing and distributing the leverage of the braces C and F upon said head, 70 which for some purposes is advantageous in that it enables the head to withstand a greater strain occasioned by end thrusts.

It is also obvious that the section G, instead of being made in a separate piece, might 80 constitute a part of the brace-tube F by being an enlargement thereof, or by said tube being reinforced at this point, and, if found desirable, the saddle-bar I might be clamped or otherwise fastened at its center to the brace-tube F, in which case the cushion-block V could be omitted.

Other modifications might be made without departing from the spirit of my invention, and I therefore wish it distinctly understood 90 that I do not limit myself to the exact design and construction here shown and described.

Having thus fully described this invention, what is claimed as new and useful is—

1. In combination with a bicycle-frame, a 95 spring saddle-bar pivoted to the head, a lug formed with the bar and fitting in a slot of the upper brace and a cushion interposed between the lug and the bottom of the slot, as and for the purpose described.

2. A bicycle-frame consisting of a head, an upper curved brace, a saddle-bar attached to said head and resting upon said brace, and means for guiding and limiting the movements of the rear end of the bar, as specified.

3. The herein-described bicycle-frame consisting of the braces C and E, head A, curved brace F having a central section G which is slotted, a spring saddle-bar attached at one end to the head, a lug H formed upon said bar for engagement with the grooved section G, and means for guiding and limiting the movements of the rear end of the bar, substantially as and for the purpose set forth.

4. In combination with a bicycle-frame of the character described, a saddle-bar I composed of resilient material and attached at J to the head of the frame, a lug H carried by said brace and arranged to enter a slot formed upon the frame, a socket carried by the rear portion of the frame, and adapted to guide the rear end of the bar, substantially as and for the purpose set forth.

5. The herein-described combination of the head A, braces C and E, curved brace F, 125 slotted section G forming a part of the last-named brace, a spring-bar I attached at J to the head, a lug H formed with said bar, and fitted within a slotted section, a cushion interposed between said lug and the bottom of 130 the slot, a lug N formed with the rear portion of the bar, a socket O projecting upward from the brace F and arranged to guide the lug N, a cushion P against which the lug N is adapted

to strike, a bolt Q projecting downward from the rod I, an ear R through which said bolt passes for the limiting of the movements of the bar I, substantially as and for the purpose set forth.

6. In a bicycle-frame, a curved upper brace having a solid intermediate portion with a slot therein, a spring saddle-bar attached at one end to the head and a lug formed on said head and fitting in the slotted section, and a

cushion placed in the bottom of said slot, substantially as described.

In testimony whereof I have hereunto affixed my signature in the presence of two subscribing witnesses.

NIEL DAHL.
